ELECTRIC HAIR DRYER

Pierre Leon Decrouez, Ridley Township, Delaware, Pa., assignor to Proctor-Silex Incorporated, Philadelphia, Pa., a corporation of New York

Filed Feb. 8, 1968, Ser. No. 10,507

Term of patent 14 years

Int. Cl. D28—03

U.S. Cl. D86—10

FIG. 1

FIG. 2

FIG. 3

FIGURE 1 is a front elevational view of an electric hair dryer embodying my new design, the opposite side being substantially the same in appearance;

FIGURE 2 is a side elevational view of the right side of FIGURE 1, the opposite side being substantially the same but omitting the hose fastening and control means; and

FIGURE 3 is a top plan view thereof.

The central portion of FIGURE 1 is shaded to indicate surface texture rather than indicating any specific texture.

I claim:

The ornamental design for an electric hair dryer, as shown and described.
